(57) **CLAIM**

The ornamental design for the weighted exercise pants, as shown and described.

DESCRIPTION

FIG. 1 is a front perspective view of a weighted exercise pants showing our new design.

FIG. 2 is a front view thereof.

FIG. 3 is a back view thereof.

FIG. 4 is a left side view thereof.

FIG. 5 is a right side view thereof.

FIG. 6 is a second front view thereof, showing how the unclaimed weights are inserted.

FIG. 7 is a second front view thereof, showing an alternate belt loop style.

FIG. 8 is a third front view thereof, showing the unclaimed weights within the pockets, and showing the crotch section in a stretched configuration; and,

FIG. 9 is a second back view thereof, showing the central buttocks section in a stretched configuration.

The broken lines illustrate environmental structure and form no part of the claimed design. An unclaimed belt is shown in broken lines to illustrate where a belt could be inserted. It is understood that the broken lines within the claimed design indicate stitch lines which form part of the claimed design.
